DESIGN FOR A PITCHER

Harold Taft Homan, San Antonio, Tex., assignor
to Alamo Pottery, Inc., San Antonio, Tex.

Application February 12, 1946, Serial No. 126,526

Term of patent 14 years

(Cl. D44—21)

To all whom it may concern:

Be it known that I, Harold Taft Homan, a citizen of the United States, residing at San Antonio, in the county of Bexar and State of Texas, have invented a new, original, and ornamental Design for Pitchers, of which the following is a specification, reference being had to the accompanying drawing, forming part thereof, in which

Fig. 1 is a top plan view of a pitcher showing my new design.

Fig. 2 is a side elevation.

Fig. 3 is an end elevation showing the mouth of the pitcher, and

Fig. 4 is an end elevation showing the handle of the pitcher.

The characteristic features of my design reside in the portions shown by means of full lines in the drawing.

I claim:

The ornamental design for a pitcher, as shown and described.

HAROLD TAFT HOMAN.
